H. A. WALLACE

RAILWAY TRAFFIC CONTROLLING APPARATUS

Filed March 1, 1924

INVENTOR:

H. A. Wallace,
by A. L. Varnell
his attorney

UNITED STATES PATENT OFFICE.

HERBERT A. WALLACE, OF EDGEWOOD BOROUGH, PENNSYLVANIA, ASSIGNEE TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed March 1, 1924. Serial No. 696,839.

To all whom it may concern:

Be it known that I, HERBERT A. WALLACE, a citizen of the United States, residing at Edgewood Borough, in the county of Allegheny and State of Pennsylvania, have invented certain new and useful Improvements in Railway-Traffic-Controlling Apparatus, of which the following is a specification.

10 My invention relates to railway traffic controlling apparatus, and particularly to apparatus of the type comprising train-carried governing means controlled by currents in the trackway. More particularly the present 15 invention relates to the trackway portion of such apparatus.

I will describe one form of apparatus embodying my invention and will then point out the novel features thereof in claims.

20 The accompanying drawing is a diagrammatic view showing one form of trackway apparatus embodying my invention.

Referring to the drawing, the reference characters 1 and 1^a designate the track rails of a railway along which traffic normally moves in the direction indicated by the arrow. The track is divided by insulated joints 2 in both rails into a plurality of successive blocks, of which only one complete 30 block A—C is shown in the drawing. Located in this block A—C is a switch D leading into a siding E, and immediately in advance of the switch D the two track rails 1 and 1^a are divided by insulated joints 2, so that the block A—C is made up of two 35 sections A—B and B—C, which I will term the "forward" and the "rear" section, respectively.

As here shown, alternating propulsion current is furnished by a generator G^p, one terminal of which is connected with a third rail or trolley 19, and the other terminal of which is connected with the middle point of an inductive bond 7 bridged across the two rails 1 and 1^a. This propulsion current is conducted around the insulated joints 2 by means of inductive bonds 6, one of which is connected across the two track rails 1 and 1^a adjacent each end of each section. The middle points of each two adjacent inductive bonds 6 are connected by a conductor 8. As is well understood, the bonds 6 and conductor 8 will conduct pro-

pulsion current freely from section to section, but will oppose the flow of alternating 55 track circuit current from rail to rail within in each section.

The forward section A—B is provided with a track circuit comprising a transformer T^a the secondary of which is connected 60 across the rails at the exit end of the section, and a track relay R^a connected across the rails at the entrance end of the section. The primary of transformer T^a is supplied with alternating track circuit and 65 train governing current from a transformer E, the primary of which is constantly supplied with alternating current from a generator G^s through the medium of a transmission line 18. The relative polarity of the 70 current supplied transformer T^a is controlled by contacts 3 and 4 of a track relay R^a connected with the rails of the block immediately to the left of point A. When relay R^a is energized, the circuit for the 75 primary of transformer T^a is from the secondary of transformer E, through wires 20 and 21, front contact 4 of relay R^a, wires 9 and 10, primary of transformer T^a, wires 12 and 11, front contact 3 of relay R^a, and 80 wires 22, 23 and 24 to the secondary of transformer E. The current which is then supplied to the rails of section A—B is of what I will term "normal relative polarity". When track relay R^a is deenergized, the 85 circuit for transformer T^a is from the secondary of transformer E, through wires 20 and 21, back contact 3 of track relay R^a, wires 11 and 12, primary of transformer T^a, wires 10 and 9, back contact 4 of relay R^a, 90 and wires 25, 23 and 24, to the secondary of transformer E. The current which is then supplied to the rails of section A—B is of what I will term "reverse relative polarity". The rear section B—C is pro-

vided with a track circuit comprising a transformer T^b the secondary of which is connected across the rails adjacent the exit end of the section, and a track relay R^c connected across the rails adjacent the entrance end of the section. The primary of transformer T^b is supplied with alternating current from the secondary of transformer E, through the pole-changing contacts 3 and 4 of track relay R^a, and this supply is controlled by the front contact 5 of track re-

lay R^B and by a circuit controller 16 operated by the switch D and closed only when this switch is in normal position, that is, in position for traffic from point C to 5 B. The circuit for the primary of transformer T^B passes from wire 11, through wire 13, primary of transformer T^B , wire 14, front contact 5 of track relay R^B , wire 15, circuit controller 16, and wire 17 to 10 wire 9. It will be seen, therefore, that current is supplied to the rails of section B-C only when section A-B is unoccupied and switch D is in the normal position, and that the current thus supplied to section B-C 15 will be of normal or reverse relative polarity according as track relay R^A is energized or de-energized.

Local train governing current is supplied to the rails of block A-C by a transformer 20 F, the primary of which is constantly connected with the secondary of transformer E. One terminal of the secondary of transformer F is connected by wire 26 with the conductor 8 at point C, while the other terminal of this secondary is connected by wire 27 with conductor 8 at point A. It follows that local train governing current is constantly supplied to the rails of block A-C and that this current flows through the two 30 rails 1 and 1^a in multiple. It is, of course, understood that the inductive bonds 6 and the conductor 8 at point B freely transmit this local current around the insulated joints 2 in the same way that these elements transmit propulsion current around such joints. 35

The trackway apparatus shown in the drawing is intended for co-operation with governing apparatus carried by a train in such manner that when the train occupies a 40 portion of track which is supplied with track circuit current of normal relative polarity and also with local current a proceed indication is given aboard the train; that when the train occupies a portion of track which 45 is supplied with track circuit current of reverse relative polarity and also with local current, a stop indication is given aboard the train; and that when the train occupies a portion of track from which the supply 50 of either track circuit or local current has been discontinued, a stop indication is also given aboard the train. It follows that both the track circuit current and the local current are used as train controlling currents. 55

The operation of the apparatus as shown in the drawing is as follows: When the block A-C is unoccupied, and the switch D is in normal position, a train passing 60 through this block will receive a proceed or a stop indication throughout the entire length of the block according as track relay R^A for the block next in advance is energized or de-energized. If section A-B is occupied, also a train entering section B-C 65 will receive a stop indication because the

supply of track circuit current to this section is discontinued at contact 5 of track relay R^B . If switch D is reversed, a train entering section B-C will receive a stop indication because the supply of track circuit current to the rails of this section is discontinued at circuit controller 16. If, however, switch D is moved to the reverse position while a train occupies section A-B, such train will not receive a stop indication due to the reversal of switch D because this switch does not control the supply of track circuit current to the rails of section A-B. 70 75

One important feature of my invention is the fact that if the switch D is reversed immediately after a train has passed such switch, it will have no effect upon the indication given aboard the train, and that I accomplish this result without interrupting the local current supplied by the secondary 80 85 of transformer F.

It should be pointed out that the distance between the switch and point B should be less than the total length of the shortest train operated over the stretch shown since 90 if it were not, a train after passing the switch and before reaching section A-B would receive a stop indication if the switch were reversed behind the train.

As shown in the drawing, each block is 95 provided with a wayside signal S, but inasmuch as these signals form no part of my present invention I have omitted the means for controlling them in order to simplify the disclosure. 100

Although I have herein shown and described only one form of apparatus embodying my invention, it is understood that various changes and modifications may be made therein within the scope of the appended 105 claims without departing from the spirit and scope of my invention.

Having thus described my invention, what I claim is:

1. In combination, a block of railway 110 track divided into a forward section and a rear section, a switch in said rear section, a track relay for said forward section, and means controlled by said relay and responsive to the position of said switch for at 115 times supplying said rear section with track circuit current.

2. In combination, a block of railway track divided into a forward section and a rear section, means for supplying track circuit current to the front end of said forward section, a track relay connected with the rear end of said forward section, a switch capable of assuming a normal or a reverse position and located adjacent the front end of said rear section, and means controlled by said track relay and responsive to the position of said switch for at times supplying track circuit current to said rear section. 120 125

3. In combination, a block of railway 130

- track divided into a forward section and a rear section, means for supplying track circuit current to the front end of said forward section, a track relay connected with the rear 5 end of said forward section, a switch capable of assuming a normal or a reverse position and located adjacent the front end of said rear section, and means for supplying track circuit current to the rails of the rear 10 section when said track relay is energized and said switch is in the normal position.
4. Trackway apparatus adapted for co-operation with train carried governing means arranged to indicate proceed when 15 the track occupied by the train is supplied with local current and also with track circuit current but to indicate stop when either or both of such currents is interrupted, said apparatus comprising a block of railway 20 track, comprising a forward section and a rear section, a switch located adjacent the front end of said forward section, means for supplying local current to the rails of the entire block, means for supplying said forward section with track circuit current, a track relay for said forward section, and means controlled by said relay and by said 25 switch for supplying track circuit current to said rear section.
- 30 5. In combination, an electric railway comprising an insulated block divided into a forward and a rear track section by insulated joints, inductive bonds for conducting the propulsion current around the insulated 35 joints separating said sections, means for supplying local train controlling current to the two track rails in multiple throughout the length of said block, an alternating current track circuit for said forward section, 40 a switch located in said rear section, and means controlled jointly by said track circuit and said switch for supplying alternating track circuit current to the rear section.
6. Railway traffic controlling apparatus comprising a block of railway track divided 45 into a forward and a rear section, means controlled by traffic conditions in advance of said block for supplying track circuit current of normal or reverse relative polarity to the rails of both of said sections, a switch 50 located in said rear section, and means for discontinuing the supply of track circuit current to the rails of the rear section when the forward section is occupied and also 55 when said switch is in reverse position.
7. Railway traffic controlling apparatus comprising a block of railway track divided into a forward and a rear section, means controlled by traffic conditions in advance 60 of said block for supplying track circuit current of normal or reverse relative polarity to the rails of both of said sections, a switch located in said rear section, and means for controlling the supply of track 65 circuit current to the rails of the rear section by traffic conditions in the forward section and by said switch.
8. In combination, a stretch of railway track divided into a forward section and a rear section, a switch in said stretch capable 70 of assuming a normal or a reverse position and so located that the distance between said switch and the junction of said sections is less than the length of the trains using 75 such stretch, and means for supplying track circuit current to said rear section only when said switch is in the normal position but for supplying track circuit current to said forward section independently of said 80 switch.

In testimony whereof I affix my signature.
HERBERT A. WALLACE.
